UNITED STATES PATENT OFFICE.

FRANS HENRIK AUBERT WIELGOLASKI, OF CHRISTIANIA, NORWAY.

STRETCHING OUT DOUBLE OR MULTIPLE ELECTRIC ARCS.

1,287,808.

Specification of Letters Patent.

Patented Dec. 17, 1918.

Application filed September 28, 1916. Serial No. 122,624.

To all whom it may concern:

Be it known that I, FRANS HENRIK AUBERT WIELGOLASKI, a subject of the King of Norway, residing at Odins gate 1, Christiania, in the Kingdom of Norway, have invented certain new and useful Improvements in Stretching Out Double or Multiple Electric Arcs, of which the following is a specification.

10 It is a well-known fact, that highly heated and electrically ionized air and other gases are comparatively good electric conductors, whereas cold gases oppose a high resistance to the electric current. To this circumstance is due the result that under ordinary conditions it is extremely difficult to stretch out long electric arcs into double-shape, because the air between the legs of the arc becomes highly heated and ionized and 15 thereby becomes also so good an electric conductor that the electric energy may relatively easily strike from one arc leg to the other.

The present invention relates to a method 25 and appertaining arrangements, which not only *per se* constitute an independent arc-extension-method but which also will assist the extension or elongation of the arc to a high degree, when used in combination 30 with other arc-extending means, such as magnetic extension or the like.

The present method consists in this that on the whole length of the arc path the comparatively cold and electrically bad conducting gases are blown in across through the space between the arc legs from openings or slots, which for this purpose are arranged on the whole length of the furnace space. 35 Hereby it is indifferent whether the furnace 40 walls are of electrically conducting material or not, or whether any conductor is arranged in or along the furnace wall, for here the extension is effected quite independent of such sort of auxiliary means and it depends only upon the movement of the gases 45 proper and the distribution of their electric conductivity.

The movement of the gases along the arc legs in the direction toward the end wall of 50 the furnace space which is provided with the gas outlet opening, will tend to extend the arc legs longitudinally, and the badly electrically conducting gases, which in the said manner are blown into the whole space 55 between the arc legs, will only prevent the arc bight from withdrawing itself toward

the electrodes, but these badly conducting gases, on account of their movement toward the outlet opening, will also force the arc bight toward the end of the furnace space 60 (the gas outlet end) which is opposite to the electrodes. At this end of the furnace space the arc bight may be fixed by making contact with an electrically conducting connection, which replaces the arc bight proper 65 and divides the arc into two series-connected stable arcs or, in case of polyphase arcs, into a plurality of stable arcs each representing one phase.

The circumstance that the arc during its 70 extension must always pass with its bight through the badly conducting gas portion, whereas it is spared from doing so, as soon as the arc is fixed and becomes stable, will result in stabilizing the arc to a high degree 75 because thereby the resistance in the arc becomes less at the moment at which the arc has obtained its final shape.

In the accompanying drawings the Figures 1 to 3 illustrate examples of constructional arrangements for carrying out the method explained above. Fig. 4 is a section of the furnace represented in Figs. 1 and 1^a, taken at the electrode end of the furnace. Fig. 5 is an elevation of the furnace shown 85 in Figs. 1, 1^a and 4, the path of the gases in the furnace being represented by dotted arrows and Fig. 6 is a longitudinal cross section of the furnace taken on the plane 6-6 of Fig. 4. 90

Figs. 1, 2 and 3 show sectional views of furnace spaces intended for extending or stretching out double and triple arcs respectively. These sections will be the same at any place throughout the length of the 95 furnace space.

It is seen that the furnace space has a compartment for each arc leg —S—, and these compartments are on the whole length of the furnace space in connection with each 100 other through slots *p*—*p*. These slots serve as passages for the arc bight during the extending operation.

The arrows indicate how the gases pass 105 into the furnace space through the openings —*a*, *b*— and —*c*— in such a manner that the arc legs are always held separated by the just incoming comparatively cold and badly conducting gases, with which the slots *p*—*p* are always filled.

Fig. 1 shows a furnace space with gas inlet from only one side, in which the incom-

ing gases are divided against the cam —*k*— arranged on the opposite furnace wall, so that the gas current is distributed to both compartments.

5 Fig. 2 shows a furnace space, in which the gases pass in from both sides and pass by each other into either compartment.

10 Fig. 3 shows how the gas inlet is best arranged in a three-phase furnace with three 15 arc legs, one for each phase.

15 Figs. 1^a, 2^a and 3^a illustrate in sections across the furnace how an electric (for instance water-cooled) conductor —*h*— may be arranged in the slot —*p*, *p*— between the 20 furnace compartments; the said conductor is best introduced through that of the furnace end-walls, in which the electrodes are mounted, the conductor being arranged between the electrodes and extends within the 25 said slot in longitudinal direction of the furnace so far toward the other end of the furnace as it may be found to be necessary or suitable in each case. Besides there is nothing to prevent this conductor (auxiliary electrode) from being inserted from the gas outlet end of the furnace into the said slot toward the electrode end of the furnace.

30 Referring more particularly to Figs. 4, 5 and 6, a current of air is introduced at *f*, and the air exit is at the top, or opposite end of the furnace (not shown). The arc is initially struck between the electrodes *s*, and by means of the air current introduced at *f* (assisted if desired by magnets placed 35 above the furnace) is elongated, and the current of cold air being introduced at *a* forms a wall between the legs of the arc, and by the circular course of this wall of cold air, as illustrated in Fig. 4, the legs of the arc 40 are constantly wrapped in a cold layer of air, moving transversely to the length of the legs of said arc.

45 In the modifications shown in Figs. 2, 3, 2^a and 3^a, there are always two layers of cold air moving in opposite directions, each transversely to the length of the leg of the arc, between the different legs of the arc.

50 Having now described my invention, what I claim as new and desire to secure by Letters Patent is:

55 1. A process of maintaining elongated bent arcs, which comprises the step of blowing into the chamber surrounding the arc, a current of cold air surrounding the legs of the bight of such arc, whereby in a U-

shaped arc, the resistance is lower near the center of the furnace space, and the tendency of the arc to shorten itself is materially decreased.

2. In the electric-arc treatment of air by 60 an elongated bent arc, the step of blowing into the furnace around the legs of the arc a tangentially introduced current of cold air, throughout substantially the entire length of the desired path of said arc, where- 65 by the constantly-renewed wall of cold air forms an insulation against short-circuiting of the arc.

3. In a plural-compartment arc furnace, 70 arcing electrodes at one end located in the separate compartments, tangential air inlet slots to the compartments, said slots extending lengthwise of the furnace for wrapping the legs of the electric arc in a constantly renewed layer of cold air capable of acting 75 as an insulator.

4. In a plural-compartment arc furnace, 80 arcing electrodes at one end located in the separate compartments, tangential air inlet slots to the compartments, said slots extend- 85 ing lengthwise of the furnace for wrapping the legs of the electric arc in a constantly renewed layer of cold air capable of acting as an insulator, and an auxiliary electrode mounted in a slot connecting the several com- 90 partments of the furnace, and independent of the slot for introducing the cold air.

5. In the electric treatment of gases by 90 long bent arcs, the step of maintaining, between the bends of the arcs, insulating walls 95 of transversely moving cold gases to prevent short-circuiting of the arc upon itself.

6. In the arc treatment of gases with bent arcs, the step of preventing short-circuiting 95 of the arcs by separating the legs thereof, by a plurality of walls of cold gases moving in opposite directions to each other, helically-tangentially around the arc bight and transversely thereto, whereby the legs are each insulated from the other leg or legs 100 by two oppositely moving cold insulating walls of gas.

In testimony whereof I have signed my name to this specification in the presence of two subscribing witnesses.

FRAÑS HENRIK AUBERT WIELGOLASKI.
